(57) **CLAIM**

The ornamental design for a wall frame extrusion, as shown and described.

DESCRIPTION

FIG. 1 is a fragmented front, top, left side perspective view of a wall frame extrusion embodying our design;

FIG. 2 is a top plan view thereof, the bottom plan view of the wall frame extrusion being a mirror image thereof;

FIG. 3 is a reduced fragmented rear elevational view thereof;

FIG. 4 is a reduced fragmented left side elevational view thereof;

FIG. 5 is a reduced fragmented front elevational view thereof; and,

FIG. 6 is a reduced right side elevational view thereof; it being understood that the wall frame extrusion has been broken along one end as an indication of indeterminate length.
